RELAY DEVICE

Howard R. Jaquith, Rochester, N.Y., assignor to Taylor Instrument Companies, Rochester, N.Y., a corporation of New York

Filed Oct. 11, 1965, Ser. No. 494,848
8 Claims. (Cl. 137—625.6)

ABSTRACT OF THE DISCLOSURE

One side of a first piston is connected to one side of a second piston by a stem, and the effective area of the first piston is larger than that of the second piston. A body provides corresponding bores for said pistons, said pistons and bores being coaxially arranged. A pilot valve means provides for connecting bore space between the pistons to bore space on the other side of the larger piston, or for sealing of one said space from the other, and exhausting the latter space to atmosphere. A fluid pressure motor and a fluid pressure source also communicate with the between-piston space. When the pivot valve disconnects the said spaces, the net force on the pistons drives the larger piston into its space, which results in the smaller piston moving to a position where it is between the connections of motor and pressure source, the latter being located such as now to be on the other side of said smaller piston, whose bore opens into atmosphere at said other side. When the pilot valve connects the first said spaces, the pressure source acts on both sides of the larger piston. The said one side of said larger piston is diminished in effective area by the stem, and the pressure on the other side of said larger piston forces it outwardly of its bore space, moving the smaller piston to a place where the motor now connects to the between-piston space and therefore with the fluid pressure source.

This invention relates to relay devices such as the valve disclosed in U.S. Letters Patent No. 2,261,287 to William J. Brown and Evan A. Edwards, dated Nov. 4, 1941.

One object of the invention is to provide a new and improved relay device for controlling the connections between a pressure fluid utilization means and various pressure fluids.

Another object of the invention is to provide a new and improved relay device wherein the said device is actuated by force due to pressure fluid and said pressure fluid also provides the bias needed to create said force.

It is also an object of this invention to provide a new and improved form of construction for such relay device, wherein such construction is characterized by economy, simplicity, ease of manufacture, efficiency and reliability.

These and other objects of the invention will be apparent from the detailed description to follow and from the claims appended hereto.

Briefly, a relay device according to the invention consists essentially of a simple casing, incorporates a pair of pressure-movable walls, and has a simple pilot valve externally operated for controlling distribution of pressure fluid to said walls. One of said walls has a larger effective area than the other, the said other thereof provides valve means for connecting pressure fluid to utilization means, and both are connected together to move as a unit. The said casing has but few external connections to sources of pressure fluid and but two pressure fluid seals between it and said walls.

In the drawing, FIGURE 1 is a partly sectional view of a relay device in accordance with the invention; FIGURE 2 is a sketch showing the relay device according to the invention in an aspect of its operation not shown in FIGURE 1; FIGURE 3 is a sketch of a modified form

2

of relay device in accordance with the invention; FIGURE 4 is a partly sectional view of a relay device in accordance with the sketch of FIGURE 3; FIGURE 5 is an end-view of the device of FIGURE 4.

5 In FIGURE 1, reference numeral 1 generally denotes a relay device according to the invention. The use of this kind of device is typically to connect a source 2 of air under pressure with a bellows 3, or other pressure fluid operated device, in order to cause the bellows to expand and in so doing, to do work in proportion to the difference between the pressure inside the bellows and the pressure outside the bellows. Thus, we may suppose the left-hand end of the bellows to be fixed to some immovable place 4 and to expand toward another immovable place 5, overcoming resistance to such expansion, such resistance being symbolized as a spring 6, interposed between place 5 and the right-hand end of the bellows so that if bellows 3 expands, the spring is compressed. For example, bellows 3, places 4 and 5, and spring 6 are analogous to the valve V of the Brown and Edwards patent, identified above, operation of which requires that the valve-actuating pressure do work to overcome various resistances, such as friction, springs, pressures, etc., in operating the valve.

10 25 At other times, it is desired to release to atmosphere the air from bellows 3, so that the bellows contracts, whereby work is again performed as a result of releasing the force stored up in spring 6.

20 30 Relay device 1 comprises a pilot valve block 7 and a control valve block 8. Block 7 has passages 9, 10 and 11 therein. Passage 9 opens at the surface of the block 7 at one end, and terminates inside the block 7 with its other end opening into one end of passage 10, which is entirely within the block. (Normally, passage 10 would be formed by drilling through one side of the block and closing the opening in the side thereafter.) Passage 10 opens at its other end into a passage 11 which opens at one end in the lower face of block 7, and at its other end opens into the bottom of a counterbore 12 opening at the upper face of block 7.

35 40 45 Passage 11 has a movable stem 13 therein which terminates at its end in respective valve plugs 14 and 15, said plugs being formed to substantially seal the ends of passage 10 when one or the other is seated in one of said ends. Conveniently, the passage 11 is cylindrical, and the block surfaces surrounding its ends are flat. The plugs are then provided in the form of spheres of greater diameter than the passage 10, whereby when a plug is seated in an end of passage 10, the plug will substantially completely close off the passage 10 at the end in which it is seated. Also, the stem may have one of its ends threaded (not shown) so that the corresponding plug may be removably secured thereto by means of a tapped hole therein (not shown) into which the threaded end of the stem 13 is screwed, and thereby allowing the stem 13 and plugs 14 and 15 to be assembled to block 7 in the manner illustrated. Since the main function of the stem 13 is to cause the plugs 14 and 15 to move substantially in unison, it need not necessarily be attached thereto. In such case, it would be necessary to provide suitable means for guiding plug 14 into and out of seating position.

40 45 50 55 60 65 70 75 80 85 90 95 Control valve block 8 has passages 16 through 21 therein. One end of passage 16 opens into the bottom of a counterbore 22 opening at the lower surface of block 8, and the other end of passage 16 opens into one end of a passage 17, the other end of which opens into the side of passage 18. Passage 18 runs downward from the top surface of block 8, merging inside block 8 with a larger diameter passage 19 whose other end opens at the lower surface of block 8, to define one overall passage extending vertically through the block 8.

A passage 20, which may be a continuation of passage 17, opens into one side of passage 18, as does a passage 21. Respective pipes 22 and 23 are connected to passage 18 via passages 20 and 21, to provide for transfer of air to and from the source 2 and to and from the interior of bellows 3. Pipes 22 and 23 may, of course, be much longer than indicated in the figure.

The blocks 7 and 8 are mated together at the top surface of the former and the bottom surface of the latter, a gasket 24 being provided therebetween so that when the screws or similar means (not shown) used for fixing the blocks together are applied, an hermetic seal between the mating surfaces of the blocks results.

Counterbores 12 and 22 are so located that their openings coincide with each other so as to define a chamber permitting sufficient freedom of motion for plug 15 to allow seating of plug 14 in the lower end of passage 11. Passage 19 is so located that the passage 9 registers with, i.e., opens into the opening made in block 8 by passage 19. Gasket 24 is, of course, perforated to provide holes matching the openings of counterbore 22 and passage 19.

Passages 18 and 19 provide the bore of a cylinder having therein a plunger or piston unit 25, which is designed for reciprocation along such bore in the general fashion of a piston. Piston unit 25 includes a piston 26 and a piston 27 integrally connected together by means of a stem 28, and respectively sealed by O-rings 29 and 30 to the inner walls of passages 18 and 19, so that though the pistons slide along their respective passages and need not have a close fit thereto, the O-rings substantially prevent leakage of air past the pistons.

As shown in the drawing, piston 27 is as far up as the vertical dimension of passage 19 will allow it to go, and plug 14 is represented as seating in the lower end of passage 11. As the spacing between pistons 26 and 27 is such that passages 17, 20 and 21 open into the annular space in bore 18 surrounding the portion of stem 28 between pistons 26 and 27, and since the plug 15 is clear of upper end of passage 11, therefore air from source 2 pervades all the described passages in the blocks 7 and 8, save for a small portion of passage 18 above piston 26.

By way of example, source 2 may be considered to be a compressor, or the like, adapted to supply air under a pressure of 20 p.s.i.g. (pounds per square inch over atmospheric pressure), or more, to a volume such as the said passages, piping 22 and 23, and the interior of bellows 3 provide, and to maintain that pressure in said volume despite a certain amount of leakage therefrom, occasional exhausting of that volume to a lower pressure region such as the atmosphere, and/or air consumption by the utilization device connected to passage 21. As the relay device 1 is normally located in the atmosphere, it is evident that piston unit 25 is biased into the position shown in FIGURE 1 by a force equal to the effective area of piston 26 times the difference between atmospheric pressure and the pressure of the air supplied by source 2, the said effective area being substantially that of the cross section of passage 18 which, for convenience, along with passage 19, may be considered to be circularly cylindrical in form with FIGURE 1 therefore representing a diametral cross-section on the common axis of passages 18 and 19.

Taking the pressure external to bellows 3 to be atmospheric, it will be evident that the bellows 3 will be extended a certain amount (depending on the strength of spring 6 and other resistance, if any) by a force equal to the effective area of bellows 3 times the difference between the pressure of the air therein and the atmosphere.

If plug 15, however, is caused to seat in the upper end of passage 11, so that the plug 14 is moved out of the lower end of passage 11, the air in the portion of passage 19 beneath piston 27, and in passage 10 and passage 11 will escape to atmosphere, and atmospheric pressure will reign in this region. Consequently, the net force on piston unit 25 will be reversed, for the net force tending to hold it in the position shown in FIGURE 1 is equal to atmos-

pheric pressure, and the net force tending to move it out of the last said position will be equal to the difference in effective areas of the pistons 26 and 27 times the pressure of the air supplied by source 2. In fact, by choosing the diameters of the passages 18 and 19 such that the cross-sectional area of the latter is twice that of the former, the magnitude of the net force acting on unit 25 will be the same no matter which of plugs 14 and 15 is seated in the corresponding end of passage 11. However, the direction of this force will be toward the open end of passage 18 if plug 14 is seated, but toward block 7 if, instead, the plug 15 is seated. Due to the seals provided by O-rings 29 and 30, the effective areas of the pistons are the same as the cross-sectional areas of the respective passages containing the pistons.

When the plug 15 is seated, the resultant net force pushes piston 27 as far toward block 7 as it can go (it is desirable to provide some irregularity on the surface of the bottom of piston 27, or like expedient, to prevent the piston 27 from fitting too closely to, or to keep it just out of contact with the upper block of block 7), i.e., substantially all the way to the top of block 7, the location of the openings of passages 17, 20 and 21 in passage 18, and the spacing between pistons 26 and 27 are such that the O-ring 29 passes over the opening of passage 21 into passage 18, and attains a position in passage 18 where it prevents transfer of air between passages 20 and 21 via passage 18. Consequently, the passage 21 now opens into that part of passage 18 above piston 27 that is open to the atmosphere, and the air inside bellows 3 now vents to atmosphere and the spring 6 releases the energy stored in it and compresses the bellows. Passages 17 and 20, however, remain in communication with each other via the annular space around that part of stem 28 that lies between pistons 26 and 27.

Since in practice it is found that a pressure of 5 p.s.i.g. from source 2 is enough to move piston unit 25 in one direction or the other, in spite of O-ring friction, inertia effects, or the like, and since as a rule the usual source 2 is more likely to be capable of providing pressure at 100 p.s.i.g. than even 20 p.s.i.g., therefore the action of piston unit 25 can be quite powerful and quite positive, even though the dimensions of the relay device be relatively small. (Save for minor idiosyncrasies of form, that would result from machining the blocks 7 and 8 to produce the various passages, FIGURE 1 follows manufacturing dimensions closely but is about twice as large as life.)

It will also be observed that the tolerances involved in making the relay device are quite liberal in general. Thus, pistons 26 and 27 need fit their respective passages no more closely than necessary to obviate the possibility of the O-rings 29 and 30 being extruded between the pistons and the passage walls by such pressure drops as may obtain across the O-rings, in use of the relay device.

In practice, the O-rings 29 and 30, the respective annular grooves 26a and 27a receiving said O-rings, and bores 18 and 19, are so dimensioned as to provide what is known in the prior art as "floating O-ring seals" for pistons 26 and 27. The opening of passage 21 into passage 18, i.e., the intersection of the cylindrical surfaces defined by those passages, is deburred, and both O-ring 29 and O-ring 30 are lightly lubricated. As a result, piston unit 25 is capable of millions of cycles of smooth, relatively friction-free movement despite the rubbing of the O-rings on metal surfaces and the passing of O-ring 29 across the opening of passage 21 into passage 18, and without maintenance other than an occasional renewal of the lubrication of O-rings 29 and 30.

The lower surface of block 8 and the upper surface of block 7 must be sufficiently smooth and mate well enough together that the gasket 24 can seal these surfaces together. The plugs 14 and 15, moreover, and the ends of passage 11 should be finished relatively accurately and smoothly, since the valving action here involves a metal to metal

contact. It should be noted, however, that insofar as operation is concerned, the minimum pressure needed for operation can be so small compared to that usually available that leakage is of no moment provided that the pressure in bellows 3 can be raised to a high enough level for it to do the work demanded and provided that wasting the capacity of source 2, in leaking air, is not objectionable. Routine drilling and finishing operations, however, suffice to provide a substantially leakless structure in which substantially no air is consumed except the air lost by exhausting the portion bore 19 below piston 27, for the purpose of moving the piston unit 25 down to where piston 27 bottoms at the lower end of passage 19, and the air transferred to the bellows 3.

Since the force on piston unit 25, due to pressure, reverses whenever the pilot valve in block 7 is actuated as described, no biasing spring (such as spring 17 of the above-identified Brown and Evans patent) is required.

For operating the pilot valve, there may be provided a lever 31 pivoted at 32 (say, a part of block 7, in effect). As shown, lever 31, which would be more or less rigid, has a spring blade 33 fixed by one end to lever 31 near pivot 32. A reverse bent end 34 of lever end provides a seat for the free end of spring which is arranged so that it would press against said end 34 save for a member 35, represented as deflecting blade 33 upward. The stiffness and initial position of spring 33 are chosen such as to provide an initial force which is a little more than is required to prevent it from bending if sufficient force is applied thereto so as to deflect lever 31 upward and cause plug 14 to seat in the end of passage 11 and to stay seated. The force tending to unseat the plug 14: its weight (and that of plug 15 and stem 13) and the pressure drop thereacross when seated, is small. Insofar as the influence of weight is concerned, this is sufficiently slight that the operation of the relay device is unaffected by its orientation.

Member 35 represents part of an entity capable of moving member 35 farther than is necessary, or possible, to move the plug 14, without some inconvenience or even damage to such entity or to the relay, unless the excess motion is somehow accommodated. As shown, spring 33 absorbs excess motion of member 35, as it can deflect safely and without consequence for a considerable distance.

It is easy to see from the foregoing that once member 35 retreats far enough from blade 33, the pressure drop across plug 14 unseats it (gravity aids also, if vertical in the drawing is taken to represent the vertical in practice) about as quickly as the retreat of member 35 permits, and plug 15 seats very shortly thereafter, thus sending piston unit 25 down.

From the description herein, it is evident that piston 26 and O-ring 29 represent a movable wall responsive to pressure and, as well, a valve acting as means for connecting bellows 3 to either one of two sources of pressure fluid, namely, the atmosphere and source 2.

Considering that the relay device has four passages or connections via which pressure or pressure fluid can be applied to it and/or admitted to it, it is evident that there are other possibilities in the way of pressure and pressure fluid sources with which the relay device may be used. Thus, source 2 may be an evacuating device, i.e., a source of air at say about 9-10 p.s.i. absolute pressure or less (i.e., a pressure that is less than atmospheric by 5 p.s.i. or more). In this instance, piston unit 25 would be in the position shown in FIGURE 1, but with the plug 15 seated and the plug 14 unseated as in FIGURE 2, whereas with the plugs positioned as shown in FIGURE 2, the piston unit 25 instead would be in the position shown in FIGURE 1.

Again, passages 11 and 18 need not connect to atmosphere (i.e., approximately 15 p.s.i. absolute) but to a source that provides air at 5 or more p.s.i. different in pressure level from the air of source 2. Again, as the pressure external to bellows 3 is mainly significant insofar

75 A_{26} =Effective area of piston 26

as it enters into determining how much bellows 3 expands and contracts, whereas it does not influence the force on piston unit 25, it can be of a magnitude unlike that of any of the other pressures.

5 The foregoing applies particularly to elastic fluids. In the case of inelastic fluids (i.e., liquids), it is only inapplicable to the extent that the incompressibility and liquid head effects must be taken into account. However, if source 2 is the type of source such as is usually adopted for hydraulic servo systems wherein discharge from the passages 11 and 18 is to the usual sump from which hydraulic liquid is recirculated by the source to the relay device, the said effects would be only of minor significance and would not influence the basic design of relay device appreciably, or in any way that would not be obvious to one skilled in the art.

10 As a practical matter, the structural form indicated by FIGURE 1 is to be preferred. Moreover, the dual role of piston 26 rather requires it to be such, as opposed to a diaphragm or bellows which, though each of these last is rather piston-like, in many respects, could not very well perform the same valve action, since it would have a peripheral portion sealingly fixed in place. The piston 27, on the other hand, could be replaced by a diaphragm or bellows as no valve action is involved.

15 Again, the pilot valve defined by plugs 12 and 14 and stem 13, is but one of several known types capable of performing the same function (as is also the case with the pilot valve operating mechanism including lever 13), and 20 utilization devices other than bellows 3, etc., could be operated by relay device 1. It is also evident that the various passages could be provided in the form of tubular pipes, cylindrical casings, and the like, of relatively thin-walled nature, as compared to the relatively massive blocks 25 7 and 8, in which the necessary passages are provided by drilling cylindrical holes therein.

25 Nevertheless, it will be observed that the specific relay device illustrated consists in FIGURE 1 essentially of but two moving parts, namely, piston unit 25 and the pilot valve consisting of stem 13 and plugs 14 and 15, in a monolithic stationary part, and each of said parts is in itself composed of few separate parts. Thus, the piston unit 25 need consist of but a single cylindrical element machined out of a cylindrical bar, (plus O-rings, of course).

30 FIGURE 3 shows a form of the invention wherein the relay device provides for switching between the pressure of source 2 and the pressure of an additional pressure source 102, and wherein the switching is controlled by a third pressure source 202. As will be seen by comparison with FIGURE 2, the only basic structural distinctions 35 involved are to close off, in effect, passage 17, to provide a connection 36 between the upper end of chamber 18 and source 102, and to provide a connection between the source 202 and the passage 16.

35 In this form of the invention, the pressure of source 55 202 must be greater than the sum of the pressure of source 2 and the difference between pressures of sources 2 and 102 times the ratio of the effective area of piston 26 to the effective area of piston 27. Likewise, the said sum must be greater than the pressure acting on the piston 60 27 via passage 9 when the ball 15 cuts off the pressure from source 202 (the condition illustrated by FIGURE 3). In each case, the excess must be sufficient, of course, to overcome O-ring friction, etc.

65 On the other hand, if the pressure acting on piston 27 via port 9 is atmospheric, then the pressure of source 2 could be atmospheric, that of source 102 could be infra-atmospheric, and that of source 202 could be a few p.s.i. larger than the sum of the former. Again, all three of these pressures could be much larger than atmospheric pressure.

70 More generally, the following inequality governs:

$$P_2 + \frac{A_{26}}{A_{27}}(P_{102} - P_2) + \frac{F}{A_{27}} < xP_2$$

- A_{27} =Effective area of piston 27
 P_{102} =Pressure of source 102 (or in the open end of chamber 18, FIGURE 1)
 P_2 =Pressure of source 2
 xP_2 =Pressure of source 202 expressed as a fraction x (proper or improper) times P_2 (since, of course, pressures of substantially fixed, known values are involved)
 F =Force necessary to overcome resistance of piston assembly to moving (O-ring friction, etc.)

The inequality, supra, applies to FIGURE 1, i.e., then $x=1$ and P_{102} =ambient atmospheric pressure, and to FIGURE 3, i.e., $xP_2=P_{202}$, the pressure of source 202.

It will be evident from the foregoing that the sole functional distinction of any structural consequence between the relay device of FIGURES 1 and 2 and the modification of FIGURE 3 is the provision in the latter of the two separate sources 2 and 202 of pressure for piston 27, one for each side, instead of allowing the one source 2 to act on both sides. This is due to the fact that conduit 17 is closed or eliminated. Optionally, FIGURE 3 may, for convenience, involve other structural modifications, such as closing the open end of chamber 18 and providing for connecting passage 36 through the side of block 8 in line with connections 22 and 23. Likewise, the block 7 may be replaced by a simple closure plate, and passage 9 shifted around to the side of block 8, so to speak, into alignment with passages 20 and 21, the pilot valve in block 7 being provided as a structural unit distinct from the relay device proper. These alterations would provide for manifolding all the pressure connections to the relay device, and remote location of the pilot valve, but would not bring about any change in the principles of operation as set forth in connection with the description of FIGURES 1, 2 and 3.

In illustration of the foregoing, the relay device of FIGURE 3 may be realized as in FIGURE 4 wherein reference numeral 108 denotes a block that is substantially the counterpart of block 8, FIGURE 1, and in general each FIGURE 4 counterpart of an element of FIGURE 1 has a reference numeral that is that of said element plus 100. Thus O-rings 129 and 130 correspond to O-rings 29 and 30, and so on. It may be noted that stem 126 is in effect piston 26 and stem 25 combined, that piston 129 and stem 126 fit somewhat loosely (D-rings are relied on for sealing purposes, however, in both FIGURE 1 and FIGURE 4), passage 136 is actually the counterpart of connection 36 of FIGURE 3, and what corresponds to the open end of passage 18, FIGURE 1, is closed by a sphere 37 or other plug, force-fitted into the open end of passage 118. Such distinctions as these are of no functional significance.

However, in accordance with the scheme of FIGURE 3, passage 17 is omitted. Moreover, the block 7 is replaced by a simple closure plate 38 (sealed to the block 108 by a gasket 124) in place of a valve-containing block-like block 7, thus eliminating the equivalent of passage 16 from the relay device proper. Block 108 has a projection 38 thereon illustrating a suitable way of keeping the piston 127 from seating its flat end surface totally on the otherwise flat plate 38. It will also be evident that the inner end of passage 119 is conical, hence the flat annular inner end surface of piston 129 cannot seat thereon substantially.

The passages 109, 128, 121 and 136 are aligned with each so as to open out on one side (preferably flat) of the block and continue on into a manifold 40 through a suitable gasket 41 sealing the manifold 40 to the block 108. The last said passages open into tapped holes 42 through 45 provided in manifold 40 for the purpose of connecting to the entities shown in FIGURE 3. Thus, a pilot valve would connect to tap 42, as one does to the passage 9, pressure sources 2 and 102 would connect to tap 43 and 45, respectively, and a bellows or the like

would connect to the tap 44. Suitable means (not shown) are provided to maintain manifold 40, block 108 and plate 38 in the assembled relation illustrated.

FIGURE 5 is an end view of the relay device of FIGURE 4, internal parts nearest the point of view being shown in broken line.

The operation of the relay device shown in FIGURES 4 and 5 is, of course, as described in connection with FIGURE 3.

In accordance with the statutes, I have described my invention with reference to the best embodiment thereof known to me thus far, and in such terms as to enable one of ordinary skill in the art to make and use it. Having done so, I wish to make it clear that the scope of my invention is to be determined with reference to the claims appended hereto, rather than by the detailed description herein of the invention.

I claim:

1. A relay device including a first wall and a second wall, said walls being connected together for motion, as a unit, along a given path, the effective areas of said walls being transverse to and spaced along said given path, so that one side of said first wall faces one side of said second wall, and the effective area of said first wall being larger than that of said second wall; first means for simultaneously providing said one side of said first wall and said one side of said second wall with first pressure fluid, said first means providing a space between said one side, said space being shaped and dimensioned such as to permit each said wall to move freely into said space without changing the effective area of said one side; second means for providing the other side of said first wall with second pressure fluid, third means for providing the other side of said second wall with third pressure fluid; and fourth means for connecting pressure fluid to utilization means when said fourth means is connected to such pressure fluid; pilot means operable to provide said other side of said first wall with pressure fluid of sufficient magnitude that the force due to pressure on said other side of said first wall is greater than the force due to pressure on said one side of said first wall plus the force due to pressure on said other side of said second wall and minus the force due to pressure on said one side of said second wall, so as to move said walls from a first position on said given path to a second position thereon; said second wall defining valve means operative when said walls are in said second position to connect said first pressure fluid to said fourth means, whereas when said walls are in said first position said valve means is operative to connect said third pressure fluid to said fourth means.

2. The relay device of claim 1, wherein said pilot means, when operated, is constructed and arranged to supply said first pressure fluid to said one side of said second wall.

3. The relay device of claim 1, wherein said valve means includes a first passage and a member therein sealingly and slidably received by said passage for movement therewith, second and third passages opening into said first passage and being spaced along the path of movement of said member, said path of movement being from a position of said member between the openings into said first passage of the said second and third passages to a position thereof beyond said openings and with the opening of said third passage being between said member and the opening of said second passage, said member constituting said second wall, and said fourth means including said third passage, and said first means including said second passage.

4. The relay device of claim 3, wherein said first wall is a member slidably and sealingly received in said first passage and in a portion of said first passage extending on the other side of the opening of said second passage from said third passage.

5. The relay device of claim 1, wherein said pilot means is a pair of plugs connected by a stem, and there being a part having a passage therein opening at each end at a surface of the part, said stem being received loosely in

said part and being of sufficient length that both of said plugs are outside the last said passage, and the said plugs being so dimensioned and shaped as to be able to seal the ends of said last said passage if seated therein, said part having a further passage therein opening at one end into the said last said passage therein intermediate the ends thereof, said first means being connected to one end of said last said passage, said second means being connected to the other end of said last said passage, and said further passage means having its other end arranged to provide pressure fluid to said other side of said first wall.

6. A relay device including a block, said block including four openings at one external surface area thereof, there being a bore in said block connected by first passage means at one end thereof to one of said openings, a pressure responsive first wall closing said bore and movable therewith, second passage means connecting a second of said openings and opening into said bore at a place where said first wall is between said place and said one of said openings, a pressure responsive second wall closing said bore and movable therewith and so located that said place is between said first wall and said second wall, third passage means opening into said bore between said second passage means and said second wall; fourth passage means opening into said bore on the other side of said second wall from said first wall, said third passage connecting a third of said openings with said bore and said fourth passage means connecting a fourth of said openings with said bore; the openings into said bore of said second and third passage means being so located along the line of movement of said second wall that said second wall is between the last said openings at one position in its path of movement, and at another position in its said path of movement said second wall is between the openings into said bore of said third and fourth passage means; said second wall

being in the form of a piston slidably sealingly received in said bore and having a lesser effective area than said first wall; both said walls being effectively rigidly connected together with respect to line of movement of said second wall.

5 7. The relay device of claim 6, wherein said first wall is also in the form of a piston slidably sealingly received in said bore.

10 8. The relay device of claim 6, including a manifold plate sealed to said one surface area, said plate having four tapped openings corresponding to the first said four openings and in registry therewith.
